UNITED STATES PATENT OFFICE

2,692,031

OIL DERRICK SUBSTRUCTURE WITH
TILTING DECK SECTION

Homer J. Woolslayer and Cecil Jenkins, Tulsa,
Okla., assignors to Lee C. Moore Corporation,
Pittsburgh, Pa., a corporation of Pennsylvania

Application October 18, 1950, Serial No. 190,694

2 Claims. (Cl. 189—21)

1

This invention relates to well drilling apparatus, and more particularly to substructures for oil well masts or derricks.

In drilling deep wells it is common practice to use a substructure upon which the drawworks unit, consisting of hoist and engines, is mounted. The substructure generally is somewhat higher than truck bed level, so various types of ramps are used to facilitate moving the drawworks unit from a truck or trailer up to the deck of the substructure, because the unit is too heavy to be lifted by the equipment usually available.

It is among the objects of this invention to provide a derrick substructure in which the deck has a self-contained ramp for elevating drawworks from a truck to the substructure deck, in which the inclination of the ramp can be adjusted for different truck bed levels, in which the ramp automatically tilts the drawworks into horizontal position, in which means are provided for holding the ramp level after the drawworks is in operating position, and in which the substructure is formed from prefabricated side frames connected by the ramp and other members that can be removed to permit the side frames to be carried side by side on a truck.

In accordance with this invention, a derrick substructure has a horizontal deck provided with a movable section extending inward from one end of the substructure and adapted to support a drawworks unit. For convenience of description, the outer end of the movable section will be said to be located at the rear end of the substructure. The front or inner end of the movable deck section is supported by a seat. The central portion of the movable deck section is pivotally supported in the substructure to permit its inner end to be lifted from the seat and its outer end to be tilted down to form a ramp for receiving a drawworks unit from a vehicle located behind the substructure below its deck level. When the center of gravity of the drawworks unit passes the pivot point of the ramp, the ramp rocks into horizontal position with its inner end resting on the seat. The ramp section then is detachably connected to the rest of the deck to hold it in horizontal position. To support the outer end of the tilted ramp at any desired height, it rests on a movable beam which is supported by jacks. The ramp or movable deck section is supported by side frames which are connected by detachable members, so that when they and the ramp are removed the side frames can be loaded on a truck for transportation to another location. For a lease move a truck can

2

be backed under the entire substructure to move it as a unit.

The preferred embodiment of the invention is illustrated in the accompanying drawings, in which Fig. 1 is a plan view of the substructure; Fig. 2 is a side view thereof without the folding floor sections, but with a drawworks unit in place on the substructure; Fig. 3 is a similar side view of the substructure with the drawworks unit resting partly on a trailer and partly on the inclined ramp section of the substructure; Fig. 4 is a view of the rear end of the substructure; Fig. 5 is a vertical section taken on the line V—V of Fig. 1; Fig. 6 is a view of the front end of the substructure shown in Fig. 2, but without the drawworks; Fig. 7 is an enlarged detail of the deck pivot taken on the line VII—VII of Fig. 1; and Figs. 8 and 9 are sections taken on the lines VIII—VIII and IX—IX, respectively, of Fig. 7.

Referring to the drawings, the substructure includes a pair of spaced parallel box-like frames A and B, each of which is formed from upper and lower beams 1 and 2 connected by vertical columns 3 and horizontal cross member 4, all welded together. The combined width of the two side frames preferably does not exceed eight feet, so that the frames can be carried over a highway side by side on a truck. At the top of each frame there is a folding floor section 5 hinged to the outer beam 1. The inner bottom beams 2 of the frames are spaced a predetermined distance apart by a pair of removable cross ties 6 and 7.

The front ends of the inner upper beams 1 of the side frames are rigidly connected by a horizontal framework 8 detachably connected to them and projecting above them. Rectangular extensions 9 are hinged to the opposite sides of this framework and normally rest on top of the side frames. The center framework and the extensions form a pipe setback support. The rear beam of framework 8 detachably supports the front end of a square support 11 for a rotary table. The rear end of the rotary table support is connected to the inner or front end of a horizontal rectangular frame 12 formed from welded structural steel beams and disposed between the tops of the side frames in the space behind the rotary table support. This rectangular frame is an independent section which forms part of substructure deck. The inner end of the frame rests on brackets 13 attached to the side frames A and B, and is detachably connected to the side frames by bolts 14, as shown in Fig. 5. The outer end of the frame is detachably connected

to the side frames by bolts 16, as shown in Fig. 4.

The central portion of frame 12 is rigidly mounted on a cross shaft 17, the ends of which are supported in bearings 18 mounted on top of short horizontal beams 19 secured to an inner pair of vertical columns 3 of the side frames A and B. The shaft usually is located a little in front of the center of gravity of frame 12, so that when the frame is freed from the rest of the substructure its outer end will tilt down and the inclined frame thus will form a ramp. The degree of inclination of the ramp is controlled by a movable beam 21, on which the outer portion of the ramp rests, as shown in Fig. 3. The ends of this beam extend between pairs of closely spaced vertical columns 3 in the side frames of the substructure, and the ends rest on jacks 22 that are located between the same columns. When rectangular frame 12 is in horizontal position, beam 21 helps to support it.

Mounted on top of the side frames beside the rotary table support 11 are shoes 23. Another pair of shoes 24 are mounted on the side frames near their rear ends. These four shoes are adapted to support a portable derrick (not shown) on the substructure in a well known manner. The derrick is raised into position and then a well is drilled with the help of a drawworks unit C (Figs. 2 and 3) mounted on the substructure. This unit includes a drawworks or hoist 26, and engines 27 for driving it and a rotary table on support 11, all permanently mounted on a skid base 28 that can be transported from one location to another on a truck trailer 29.

When it is desired to remove the drawworks unit C from the substructure and to transport it to another location, the trailer 29 is backed up to the rear end of the substructure. Rotary table support 11 and bolts 14 and 16 then are removed to free the opposite ends of the movable deck section 12 from the rest of the substructure. The base of the drawworks unit then is skidded toward the rear end of the deck until the center of gravity of the unit passes pivot shaft 17. If beam 21 now is lowered by means of the jacks, the outer end of the movable deck section will be moved down with the beam by the weight of the drawworks unit. The beam is lowered until the movable section has tilted far enough for its outer end to be at about the level of the trailer bed. The drawworks unit then can be skidded down the ramp thus formed and onto the trailer, as shown in Fig. 3.

This procedure is reversed when it is desired to transfer the drawworks unit from the trailer to the substructure. The base 28 is skidded up the ramp 12 until the center of gravity of the drawworks unit passes the pivot shaft. This tilts the inner end of the ramp down onto brackets 13 so that the movable deck section is horizontal with its upper surface in the same plane as the upper surfaces of the side frames. The opposite ends of frame 12 then are fastened to the side frames by bolts 14 and 16. The jacks are elevated to raise beam 21 up against frame 12 so as to reinforce it.

In the event that the center of gravity of the drawworks unit is nearer to its front or rear end than in the case of the one illustrated, the movable deck section either would not be tilted by it at all or would rock too soon. To avoid such situations, the bottom of the deck section 12 is provided with several longitudinally spaced bolt holes 31 (Fig. 8) to permit the pivot shaft 17 to be bolted to that section in different locations as necessary. Likewise, the bearing-supporting beams

19 are provided with several longitudinally spaced bolt holes 32 (Fig. 9), so that the position of the bearings along those beams can be changed to agree with changes in position of the shaft.

With the substructure disclosed herein, it is a simple matter to raise the drawworks and engines from a trailer to a higher level on the substructure, since lifting equipment or a separate ramp is not required. The same thing is true if the drawworks unit is to be removed from the substructure. When it is desired to transport the substructure from one location to another on the oil lease, the substructure, with the drawworks unit on it, is jacked up far enough to allow a truck trailer to be backed under it after the rear cross tie 6 has been removed. The cross tie then is replaced and the substructure is lowered onto the trailer, by which it can be hauled to its new location. In such a situation it is unnecessary to disconnect side frames A and B from each other. On the other hand, if the substructure has to be transported over a highway where it would be too wide to be carried in the manner just set forth, all of the members which connect the two side frames A and B are first removed. These are the cross ties 6 and 7, the end frame 8 and extensions 9, the movable deck section or ramp 12, and the rotary table support 11. The two side frames then are loaded on a truck beside each other and fastened together. When floor sections 5 are folded down against the sides of the side frames, the connected frames are no wider than allowed by highway restrictions. Whichever way the substructure is carried, it does not take long or much effort to remove or replace the members that have to be removed from between the side frames. The removable members are relatively small and light weight compared with the substructure as a whole and can be carried on top and inside of the side frames during transportation.

According to the provisions of the patent statutes, we have explained the principle of our invention and have illustrated and described what we now consider to represent its best embodiment. However, we desire to have it understood that, within the scope of the appended claims, the invention may be practiced otherwise than as specifically illustrated and described.

We claim:

1. In well drilling apparatus, a derrick substructure having an elevated horizontal deck provided with a movable section extending inward from one end of the substructure adapted to support a drawworks unit, means pivotally supporting said deck section to permit its outer end to be tilted down to form an inclined ramp for receiving a drawworks unit from and delivering a drawworks unit to a vehicle located at the outer end of said deck section below the deck level of the substructure, a pair of laterally spaced vertical members mounted in the substructure on each side of the pivoted deck section near its outer end, a beam extending across the substructure below said deck section and having its ends slidably mounted between each pair of said vertical members, and jacks mounted beneath the ends of said beam for supporting it and raising it against the bottom of said deck section and for limiting the distance the outer end of said section can be tilted down.
2. In well drilling apparatus, a pair of spaced parallel box-like substructure frames, means on said frames for supporting a mast, a horizontal rectangular frame disposed between the box frames at the top of the substructure and ex-

tending inward from one end, means detachably connecting the rectangular frame in fixed position to the box frames, a horizontal framework mounted between the upper portions of said box frames in front of the rectangular frame, a rotary table support between the framework and rectangular frame and detachably connected to them for support, and means pivotally supporting said rectangular frame after it has been disconnected from fixed position between the box frames and rotary table support, whereby to permit the outer end of the horizontal frame to tilt down to form an inclined ramp when the center of gravity of

a drawworks unit thereon is moved out past said pivotal means.
